United States Patent Office.

C. M. HUCKINS, OF EAST TOPSHAM, VERMONT.

Letters Patent No. 95,801, dated October 12, 1869.

IMPROVED BRIDLE-BIT.

The Schedule referred to in these Letters Patent and making part of the same.

To all whom it may concern:

Be it known that I, C. M. HUCKINS, of East Tops-
ham, in the county of Orange, and State of Vermont,
have invented a new and useful Improvement in
Bridle-Bits; and I do hereby declare that the follow-
ing is a full, clear, and exact description thereof, which
will enable those skilled in the art to make and use
the same, reference being had to the accompanying
drawings, forming part of this specification.

The drawing represents a perspective view of my
improved bridle-bit.

This invention relates to a new bridle-bit for horses,
which shall be so constructed that it may be used as
a straight rigid bit, or as a power-bit, when driving
or riding an unruly or hard-mouthed horse, and which
shall be so constructed as to give the rider or driver
full control over the horse.

The invention consists in the application of toggle-
levers to a jointed bit, as hereinafter more fully de-
scribed.

A A, in the drawing, are two jointed arms or por-
tions of my improved bridle-bit. They are connected
by a pivot, a.

Toggle-levers B B, about half the length of each
arm of the bit are pivoted to the middle portion of the
bit-arms, and are connected and jointed with each
other by a pin, b.

When the toggle-arms or levers B are pushed for-

ward, so as to lie closely along the rear side of the
main arms A, they hold the said arms securely locked,
forming a straight rigid bit.

When the toggle-arms or levers B are drawn back
into the position shown in the drawings, the bit be-
comes a jointed bit.

By this construction, when the reins are drawn upon,
the bit is forced against the tender inner sides of the
horse's jaws, and the middle or joint of the bit against
the bottom of his mouth, forcing him to yield at once
to the will of the rider or driver.

A bit thus constructed, a horse cannot hold with
his teeth. It will not cause him to open his mouth,
or disfigure him in any way, and will not slide in his
mouth, being thus invaluable for biting young horses,
subduing unruly horses, or driving hard-mouthed
horses.

Having thus described my invention,

I claim as new, and desire to secure by Letters
Patent—

The toggle-levers B B, arranged on the arms of a
jointed bit, substantially as herein shown and de-
scribed, for the purpose specified.

C. M. HUCKINS.
